UNITED STATES PATENT OFFICE.

ROLAND W. BROWN, OF NEW YORK, N. Y.

PLATFORM PUBLICITY SYSTEM.

Application filed June 19, 1923. Serial No. 646,367.

To all who it may concern:

Be it known that I, ROLAND W. BROWN, a citizen of the United States, residing at New York city, borough of Manhattan, in the county of New York and State of New York, have invented certain new and useful Improvements in Platform Publicity Systems, of which the following is a specification.

10 This invention relates to sound transmitting systems or apparatus and has particular reference to the transmission of sound in the nature of radio activities, as from a central or home station.

15 Among the objects of the invention is to provide a system of sound distribution associated with a peculiar arrangement or system of visible display stations of the representation of the figure and voice of a character at the main broadcasting station.

More specifically stated, this system has been devised with the primary object of utilizing the well known principles of radio broadcasting for political campaign parties, 25 and a further object to be attained thereby is to enable the publicity campaign committee of any political party to provide on each of any number of widely separated local platforms a figure, dummy, picture, or 30 other representation of a well known political character, such as a leading national candidate, and to arrange at, near, or within the facial portion of said figure or representation, the bell portion of a loud speaking apparatus suitably connected in a well known manner with a radio receiving outfit, so that the sounds delivered therefrom will seem to 35 come from the mouth of the figure, and which sounds will have originated directly 40 from the vocal organs of the person represented by the figure while he may be stationed at any convenient or distant headquarters, and whereby in the use of my new system such prominent or leading national 45 character will in effect be a personal attraction at each of the local rallies or events, both by appearance of his person and the actual sound of his voice while delivering a 50 public address. I wish it to be understood, however, that while my system has been devised primarily for campaign publicity purposes, the same idea may be utilized in other specific manners and for other purposes.

With the foregoing and other objects in 55 view the invention consists in the arrangement and combination of parts hereinafter

described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a diagram suggesting the act of delivering a public address by an individual, as a national political candidate, at a central station and from which the address is being broadcasted to a multiplicity of other stations, at each of which other stations is a representation of the character or individual actually delivering the address.

Fig. 2 is a front elevation of the figure mechanism at the several local stations.

Fig. 3 is a vertical section on the line 3—3 of Fig. 2.

Referring now more specifically to the drawings, 10 indicates sound receiving and transmitting mechanism such, for instance, as the well known broadcasting apparatus, suitably located either on a platform 11 or other position in convenient position for a spoken voice or the like, as from the national character A, to be delivered thereinto, while the person may be standing, sitting, or otherwise positioned for the purpose.

The sounds, as for example, the public political address, being broadcasted from the station or apparatus 10 may be picked up at any suitably located local stations or 90 through the intermediary of relay stations or super stations, according to distance to be covered, the nature of the wave length or electrical equipment, or the character of the original sound being broadcasted. The plurality of sub stations or local centers represented at A' will therefore be understood as being of any suitable nature according to the equipment or apparatus at any desired time. For the purpose of this 100 description specifically, however, these stations A' may be thought of as an indefinite number or multiplicity of local units or stations where political rallies are being held simultaneously and at which as an attraction will be the representation of the appearance and sound of some great or notable character who in person will be located at the central station and actually speaking 105 into the apparatus at 10.

The system may be developed and practised in various ways, but as a practical em-

bodiment I employ a figure or representation of the character A as by printing, painting, or otherwise placing upon a chart, screen, or other device as at 12, the representation of the speaking character. This representation may be effected upon the screen or chart in any well known or approved manner, even by light projection thereupon, as from a projection machine such as a moving picture from a moving picture machine, or a stereopticon, but the arrangement is such that that portion of the device 12 that carries or supports the facial portion of the figure shall be so arranged as to be suitable for transmission therethrough or therefrom of the sound of the individual's voice, and yet being of such a character or composition as to carry the facial representation of such person. To this end I indicate the screen 12 as provided with an opening at 13, said opening being fitted with a section of suitable reticulated or mesh fabric 14 as will serve the dual purpose above mentioned. That is to say, this portion 14 will have sufficient body to carry the representation of the speaker's face and yet will be sufficiently sheer or open to permit the sound waves to pass directly therethrough without obstruction so that the speaker's voice will be heard by the audience as coming directly from the figure.

It is well understood that in campaign activities especially, it is usual for local rallies to be held for educational and publicity purposes and for a number of local people or candidates to be assembled on the platform for the discussion of local issues and to furnish enthusiasm sufficient to attract the voters of such locality, and then for the discussion of National or State issues it has heretofore been attempted to present National or State candidates of repute as a part of the evening's program. These attempts, however, are usually unsatisfactory because of the physical impossibility for the more prominent candidates to be present at such events or for them to be on any one platform long enough to satisfy the necessity

arising from the questions to be discussed by them. By my system, however, it is obvious that any desired number of local events may be arranged by the national committee to take place at the same time in various parts of the country, and at a predetermined hour the national candidate or other person of more than ordinary importance will be announced, and, in effect, actually presented to take his place on each of the local platforms, thereby adding not only the attractiveness of his seeming appearance but the actual benefit of his actual speech and the intelligence to be expected from such character. As before indicated the figure or means carrying the figure may be of any suitable nature and preferably portable so as to be presented or interchanged readily from time to time according to the direction of the general committee or local conditions.

15 indicates the bell portion of the horn 70 of a loud speaker 16 connected up in any well known manner with a receiving outfit 17 either behind or within the device carrying the representation of the speaker. It will of course be obvious that the local committee or talent may be located at the time upon the same platform as the figure representing the national candidate.

I claim:

The herein described system of platform 80 publicity comprising the transmission from a main center of the voice of a well known character, the visual representation at the same time of said character at a number of widely spaced local points all remote from 85 said center, said visual representation consisting of a substantially full size picture upon a relatively opaque and compact material, the head portion of said picture being upon a material adapted to allow the passage of sound therethrough, and the causing 90 of the sound of the voice of said character as originated by him to emerge from the region of said head portion of said picture. In testimony whereof I affix my signature.

ROLAND W. BROWN.
